Arthur Middleton Rose

UNITED STATES PATENT OFFICE.

ARTHUR MIDDLETON ROSE, OF YONKERS, NEW YORK, ASSIGNOR TO
MATTHEW J. WHITTALL, OF WORCESTER, MASSACHUSETTS.

DESIGN FOR A RUG OR CARPET.

SPECIFICATION forming part of Design No. 23,031, dated January 30, 1894.

Application filed November 13, 1893. Serial No. 490,865. Term of patent 3½ years.

To all whom it may concern:

Be it known that I, ARTHUR MIDDLETON ROSE, residing at Youkers, county of Westchester, State of New York, have invented and produced a new and original design for a pattern to be wrought into Wilton rugs or other carpetings in such coloring as may be designed; and I do hereby declare that the illustration accompanying this specification gives and conveys to any one skilled in the art of carpet weaving and manufacture a clear understanding of the same, and is sufficient to enable such person to use my invention.

The leading or characteristic features of my design consist in the band of floral ornamentation extending across the top of the

pattern, the solid band of geometric figures lying midway between the top and bottom portion of the pattern and carrying above the same a floral spray, and having below the same isolated conventionalized stems of blossoms and leaves.

What I claim as my invention, and desire to secure by Letters Patent, is—

The design for a rug, or similar fabric, substantially as shown in the illustration accompanying.

ARTHUR MIDDLETON ROSE.
